FAUCET

Joseph Kornas, Linden, N. J.

Application November 30, 1932, Serial No. 644,947

14 Claims. (Cl. 251—27)

The invention relates to faucets or basin cocks of the type in which a floating valve is normally maintained on its valve seat by virtue of the fluid pressure at the inlet end of the faucet, with or without the assistance of springs, for maintaining the valve on its seat and in which the valve is moved off its seat to open the faucet by means of a manually actuated screw plunger.

The primary object of this invention is to 10 simplify faucets of this character and to provide a structure which will be positive in its action; which will insure an ease of movement of the valve and its actuating mechanism in moving the valve off its seat to open the faucet; which 15 will insure a quiet unobstructed flow from the discharge spout and which will insure a snug positive seating of the valve back on to its valve seat closing the faucet when released by the actuating mechanism.

20 In faucets of this character it has been found that even though they may function satisfactorily when new this satisfactory performance has but a short life and as soon as the rubber or other gaskets forming the surface between the 25 valve and its seat become worn, the faucet became noisy; a chattering and wobbling action of the valve develops; the gasket starts to wear, and eventually the faucet became leaky and the worn gasket has to be replaced from time to 30 time.

The present disclosure features a construction in which the wobbling action of the valve in its movement on to its seat is avoided; the resulting chattering is eliminated and the life of the gasket or equivalent compressible element 35 is prolonged and there is thus provided a faucet which has a materially longer life compared to known devices, before it is necessary to replace the gasket and other wearable parts.

40 Broadly this latter object is attained by providing guiding means internally engaging the valve for maintaining it in a unilateral direction of movement as it engages and disengages its valve seat.

45 The present disclosure also features a long bearing between the valve and its guiding means and the providing of a massive head of compressible material for engaging the valve seat and for providing surplus material for prolonging the time during which the sealing at the 50 valve seat is maintained.

Various other objects and advantages of the invention will be in part obvious from an inspection of the accompanying drawing and in 55 part will be more fully set forth in the following

particular description of one form of mechanism embodying my invention and the invention also consists in certain new and novel features of construction and combination of parts hereinafter set forth and claimed.

In the accompanying drawing:

Fig. 1 is a central vertical longitudinal section of a faucet constituting a preferred embodiment of the invention and showing the valve in its normal closed position; and

Fig. 2 is a similar view shown partly in side elevation and illustrating a modified form of the invention and showing the valve of Fig. 1 in open position.

In the drawing and referring indiscriminately to the showing in either figure, there is disclosed a faucet including a housing 10 which comprises a vertically disposed body portion 11 provided with the fluid inlet passageway 12 on one side and a discharge spout 13 on the other side. The faucet is provided with an attaching flange 14 encircling the inlet passageway and otherwise corresponds in general to conventional forms of water bibbs now in general use. The body portion 11 is of somewhat cylindrical form 80 with its bore divided midlength by means of a horizontally extending apertured partition 15 which divides the same into an upper discharge chamber 16 in open communication on one side with the spout 13 and into an inlet chamber 17, the lower portion of which communicates with the fluid inlet 12 by means of an inclined passageway 18. The lower end of the inlet chamber 17 is open and internally 85 screw threaded to receive a screw plug 19.

In the form of the invention disclosed in Fig. 1 the partition 15 is provided with aperture 20 and on the side thereof facing the inlet chamber the aperture is bevelled to provide a frusto-conical valve seat 21. In the form of the invention shown in Fig. 2, a cylindrical tubular cage 22, hereinafter sometimes referred to as a pressure distributor, is threaded into the upper end of the housing 10 and has its lower end engaging in a shouldered seat 23 formed in the partition 15. The lower end of the cage 22 is open and this open end is shaped to provide a frusto-conical or preferably a slightly curved concaved valve seat 24 corresponding to the valve seat 21. The peripheral wall of the cage 22 is provided adjacent its lower end with a plurality of circumferentially spaced apart ports 25 which provide a series of passageways between the interior of the cage 22 above the valve seat and an annular channel 26 formed between the exterior side of

the cage 22 and the adjacent wall which outlines the discharge chamber 16 and which channel opens on one side thereof into the spout 13.

The upper portion of the bore in the housing 5 in the showing in Fig. 1 is internally threaded, and similarly the upper portion of the bore of the cylindrical cage 22 of Fig. 2 is internally threaded. In both showings a screw plunger 27 is provided with an enlarged threaded portion 28 10 in spaced relation to its opposite ends and which is in threaded engagement with the threads of the housing or cylindrical cage so that as the screw plunger is rotated it moves axially up and down in the housing or in the cylindrical cage. 15 Below the threaded portion 28 the plunger is reduced in diameter to provide a valve engaging stem 29 the lower end of which is provided with conical recess 30 for engaging the valve as hereinafter described. The upper end of the screw 20 plunger is provided with a handle stem 31 which projects above the housing, extends through a cap 32 and is provided at its outer end with a handle 33. Suitable washers and gaskets 34 are contained within the cap as is usual in faucets 25 of this character.

A valve guiding rod 35 is secured to the screw plug 19 and extends upwardly therefrom axially along the inlet chamber 17. A valve 36 is slidably mounted on the rod and is guided thereby 30 in a unilateral direction in its movement to and from the valve seat. The valve comprises a central metallic core 37, preferably of brass, provided with a bore 38 opening from the lower end and into which the rod 35 extends for a 35 relatively long distance. The upper end of the core is solid and is provided with an axially extending conical projection 39 which is designed to have a fit in the recess 30 at the lower end of the screw plunger. It is a feature of this disclosure that the metallic end of the screw plunger 40 in its contact with the valve engages a metallic member so that there is a metal-to-metal contact between the valve and the screw plunger which actuates the same in moving it off its 45 seat to open the faucet. The brass core 37 is contained within a long sleeve 40 of rubber or equivalent compressible material of the type usually employed in forming gaskets and like valve seat engaging or forming materials. In the 50 instant case the sleeve 40 is of cylindrical form for the major portion of its length and has its upper end enlarged to form a head 41 having a peripheral configuration to conform to and engage the valve seat therefor and to provide for 55 the necessary bulk of material at the seat to compensate for wear of the rubber gasket formed by this head. A coil spring 41 encircles the rod 35 and is disposed between the screw plug 19 and the lower end of the valve to move the valve in 60 the direction to engage its seat. It is understood that the screw plug, rod, spring and valve constitute a single unit which can be demounted from the housing as a whole thus permitting the ready inspection and repair of the component 65 parts as well as to provide direct access to the valve seat for the purpose of regrinding or otherwise repairing the same.

In operation and assuming that the parts are 70 in their normal, faucet-closed position as shown in Fig. 1, it will be understood that the fluid pressure from the inlet and inlet chamber 17 acts upwardly on the relatively extensive surface provided by the underside of the valve, holds the same snugly on to its seat and thus shuts off 75 communication through the opening in the par-

tition 15. It is understood that under these conditions the screw plunger has been rotated a distance sufficient to elevate it clear of the valve and thus permit the valve to be forced on to its seat without interference from the controlling plunger and to show this condition it will be assumed that there is a clearance at 43 between the adjacent ends of the plunger and valve.

To open the faucet the handle 33 is rotated in the direction to cause the plunger to move from the inoperative position spaced above the valve as shown in Fig. 1, downwardly into engagement with the valve to press the same away from the valve seat and into the open position shown in Fig. 2. It will be understood that this action will be contra to the direction of fluid pressure which has been acting to maintain the valve seated. In those situations where there is relatively high inlet pressure the spring shown at 42 is unnecessary, but the use of the spring as herein disclosed insures the positive seating of the valve independent of the fluid pressure which acts in the same direction as the spring. The threaded portion at 28 is provided with threads having a low lead so that the valve is held locked 100 in its open position and will remain so locked in its open position irrespective of the pressure which may be acting in a tendency to close the valve and this condition will continue until the plunger is positively rotated into position to 105 permit the valve to follow it as the handle is turned in the direction to lift the plunger and thus permit the valve to move back on its seat as previously described.

It is a feature of this disclosure that the valve 110 is guided in a unilateral direction in its movement to and from its seat thus avoiding lateral shifting or wobbling which has characterized similar forms of valve constructions where the valve was free to move laterally in addition to 115 its prescribed axially longitudinal movement. The providing of an internal guide as herein disclosed provides a valve structure which is free of external projections and provides the maximum possible clearance in the annular passageway 17. At the same time the enlarged head at the valve seat end of the valve provides an extensive pressure receiving area which is greater than the corresponding cross sectional area of the opening forming the valve seat. It is a further feature of the invention that the valve is made relatively long so as to provide a long axial bearing for the valve in its guided movements.

It is possible by unscrewing the plug 19 to 120 drop the valve together with its guiding rod and seating spring from the underside of the faucet and thus facilitate the inspection or repairing of the valve and at the same time there is provided a ready access to the valve seat for any necessary regrinding or cleaning.

Referring particularly to the modified showing in Fig. 2, it is appreciated that by unscrewing the cap 32 and removing the handle 33, the gaskets 34 may be readily replaced and on the withdrawal of the entire plunger the cage 22 140 with its valve seat forming end may be unscrewed from the faucet for repair, cleaning or regrinding of the valve seat thus exposed. In the showing of the device in Fig. 2, it will be understood that the fluid in its upward movement through the annular passageway 17 passes the head of the valve on all sides of the same and then moves laterally through the four ports 25 into the passageway 26 and thus out through the nozzle. The balancing of the streams 145 150

through the opposing ports 25 has the effect of quieting the flow as it passes out through the nozzle.

Under some conditions as when the liquid controlled by the faucet is high or when the threaded engagement of the plunger with the faucet housing or cage is made loose to provide for a freedom of movement of the handle 33, the liquid has a tendency, when the valve is open, to creep up through the clearance between the co-acting threads, and this necessitates a tight packing 34 to prevent leakage out through the top of the faucet. Any tight packing at 34, of course, has a tendency to reduce the freedom 10 of rotary movement of the handle 33 and it is a feature of this disclosure to provide a handle control which is easy to operate. In a structure such as is shown in Fig. 1, when the valve is closed the liquid which has been trapped between the threads on the upper or low pressure side of the valve tends to drain back into the outlet chamber 16 and is discharged slowly drop-by-drop thus giving rise to an undesirable dripping from the spout 13. In order to avoid necessity of a tight packing at 34 and to prevent this dripping the threaded portion 28 is provided in the showing in Fig. 2 with a discharge drain slot 44 which is formed most conveniently as a straight slot in the side of the plunger, as shown, 20 but which preferably should be inclined in a spiral form to facilitate a quick flow along the same. It is obviously possible to form the slot in the threaded portion of the housing or cage and in either case there is formed a drain passageway from the gaskets 34 to the outlet chamber 16. In this case the liquid rising initially 30 in the passageway 44 tends to compress air trapped in the upper closed end of the passageway. When the valve is closed the compressed air at the top of the passageway reacts on the water column below the same to expel the water in the passageway. At the same time the water trapped between the threads is drawn into the slot 44 which provides a wide open discharge channel 40 for any water which may be above the discharge chamber 16. In practice there is a short quick spurt of liquid which flows out from the spout immediately after the valve is closed and no further drip takes place.

50 While the core 37 may be of a simple straight cylindrical form with the rubber coating 40 adhering thereto either by virtue of its elasticity or by adhesion, it is suggested that the upper portion of the core be enlarged slightly to form a bulbous head 45 which acts as a stop to prevent the fluid pressure on the lower or high pressure side of the valve seat acting on the lower end of the rubber sleeve from stripping the same upwardly off the core. In the preferred construction illustrated in Fig. 1 the head 45 is of slightly less diameter than the diameter of the opening 20 through the valve seat. Under these conditions the upper curved side 55 46 of the head coats with the similarly curved underside of the valve seat to wedge the rubber gasket forming head 41, at least to a small extent, between the core and the valve seat. The greater the fluid pressure acting on the seated 60 valve the greater will become this wedging engagement. Where there is a high fluid pressure present the parts are designed to avoid any such wedging action as will interfere with the desired ease of movement of the valve when 65 forced off its seat by rotative action of the

plunger under the desired light manual pressure acting on the handle 33.

I claim:

1. A faucet including a single casting comprising an upstanding body portion provided with a bore open at opposite ends, said body portion provided with a horizontally extending partition dividing the bore into an upper discharge chamber and a lower inlet chamber, said partition provided on its underside with a slightly curved concaved valve seat adapted to be exposed to view through the lower open end of the bore, a discharge spout opening from one side of the discharge chamber above the valve, and a downwardly inclined inlet passageway opening into the lower portion of the inlet chamber on the side thereof opposite the spout, a plug for closing the lower open end of the bore, a guide rod carried by the plug and extending axially along the inlet chamber, a floating valve in the inlet chamber telescoping the guide rod, extending across the inlet passageway opening and having its upper end fashioned to fit in said concaved valve seat, and normally maintained on said seat by the upward pressure in the inlet chamber, a screw plunger in threaded engagement with the upper portion of the bore in the body portion and provided with a stem extending across the outlet chamber and adapted to bear on the upper side of the valve to move the same off its seat, and a cap closing the upper end of the bore and through which cap the plunger extends. 80

2. A faucet comprising a housing provided with means forming a cylindrical inlet chamber open at its lower end and provided with a valve seat at its upper end, a screw plug for closing the lower open end, a guide rod secured to the plug and removable therewith, a valve comprising a metallic core and a sleeve of compressible material telescoping the core and having an end portion fashioned to engage the valve seat and said core provided with an axially extending bore into which the guide rod extends to guide the valve in its movement to and from its valve seat and a spring disposed between the screw plug and valve tending normally to maintain the valve on its seat, and said valve, spring and screw plug being removable from the housing as a unit thus exposing the valve seat through the open lower end of the faucet. 100

3. A faucet comprising a housing provided with means forming an inlet chamber open at its lower end and provided with a valve seat at its upper end, a screw plug for closing the lower open end, a guide rod secured to the plug and removable therewith, a valve comprising a metallic core and a sleeve of compressible material telescoping the core and having an end portion fashioned to engage the valve seat and said core provided with an axially extending bore into which the guide rod extends and a spring disposed between the screw plug and valve tending normally to maintain the valve on its seat. 115

4. A faucet comprising a housing provided with means forming a cylindrical inlet chamber open at its lower end and provided with a valve seat at its upper end, a screw plug for closing the lower open end, a guide rod secured to the plug and removable therewith, a valve comprising a metallic core and a sleeve of compressible material telescoping the core and having an end portion fashioned to engage the valve seat and said core provided with an axially extending bore into which the guide rod extends to guide 120

- the valve in its movement to and from its valve seat.
5. In a device of the class described, the combination of a valve housing having an annular valve seat, a fixed guide rod extending axially towards the center of said seat, a valve slidably mounted on the rod in its movement to and from said seat, a plunger extending axially of the rod and disposed to engage the valve to move the same off its seat and along said guide rod and a spring coiled about the guide rod and bearing at one end against the valve to maintain the same in engagement with said seat.
6. A faucet provided with an annular valve seat, a floating valve normally engaging said seat, relatively long bearing means for guiding the valve in its movements to and from its seat, said valve including a relatively long sleeve of non-metallic material enlarged at one end to provide a valve seat engaging head, said head providing a fluid pressure receiving shoulder on the side opposite the side engaging the valve seat, and said head providing a relatively large bulk of material to compensate for wear of the portion thereof engaging the seat and thus prolong the functional activity of the valve.
7. In a device of the class described, the combination of a valve housing having an annular valve seat, a fixed guide rod extending axially of the opening in said seat, a valve slidably mounted on the rod for movement to and from said seat, said valve including a metallic core provided with a head at the end and provided with a bore receiving the rod, said bore terminating exteriorly of the head to leave the head as a solid mass of metal and a sleeve of compressible non-metallic material secured to and telescoping the core and side of the head and adapted to engage the valve seat, the headed end of the metallic core having an exposed portion within the sleeve constituting a metallic seat for a valve unseating element.
8. A faucet including an upstanding inlet chamber open at opposite ends, an annular valve seat defining the upper end of the chamber, means for closing the lower open end of the chamber, an inlet passageway opening laterally into the side of the chamber, relatively long valvular mechanism insertable into the chamber through its lower open end, extending axially of said chamber and providing a long annular passageway between the same and the wall of the chamber, said mechanism including a centrally positioned fixed guide rod and a long valve slidably mounted on the rod and normally engaging said seat by virtue of the fluid pressure from the inlet passageway, said valve and rod providing a long bearing in the direction of movement of the valve to and from its seat.
- 60 9. A valve comprising a relatively long metal rod provided at one end with an axially extending guiding bore and with a solid head at the other end with the extreme end surface of said other end exposed to form a contacting surface for a valve unseating device, a sleeve of non-metallic material telescoping the rod and pro-
- viding means at the solid headed end of the rod for engaging a valve seat.
10. A valve comprising a relatively long metallic core, one end provided with means adapted to be engaged by a valve moving member and the other end providing a spring engaging surface, and a sleeve of non-metallic material telescoping the core, said sleeve provided at one end with an enlarged head fashioned to fit a valve seat.
11. In a device of the class described, the combination of a housing having means providing an annular valve seat, with a discharge chamber on the low pressure side of said valve seat, a valve on the high pressure side of the valve seat normally engaging said seat, a screw plunger on the low pressure side of the valve seat for unseating the valve, coacting threads providing a threaded engagement between the plunger and housing and said plunger provided with means at said threaded engagement for draining from the clearances between the threads forming said engagement back into the discharge chamber any liquid which may have been forced into the clearances while the valve was open.
12. In a device of the class described, the combination of a housing provided with a threaded bore and having a discharge chamber at one end of the threaded bore, a plunger in threaded engagement with said bore, a closure cap at the other end of the threaded bore and through which the plunger extends, a gasket in said cap for closing the adjacent end of the bore, and said plunger and threaded bore coacting to provide a drain passageway for discharging into the discharge passageway any accumulations which may be in the clearances between the threaded bore and the portion of the plunger which is contained therein.
13. In a device of the class described, the combination of a valve housing having an annular valve seat of substantially frusto-conical form, a floating valve having a portion of corresponding form for engaging said seat, said valve including a relatively long core provided with an enlarged head at the end adjacent the valve seat, and a coating of non-metallic compressible material disposed between the enlarged head and the valve seat and the portion of the coating engaging the valve seat increasing in radial cross sectional area in the direction of unseating movement of the valve.
14. In a device of the class described, the combination of a valve housing having an annular valve seat of substantially frusto-conical form, a valve having an annular head of compressible material with one side fashioned to fit said seat, and a metallic core extending axially of the valve seat and provided with a wedging head of less diameter than the diameter of the opening through the valve seat, said metallic head acting on the compressible head of the valve to cause the head to be wedged slightly between the metallic core head and the valve seat.

JOSEPH KORNAS.
